E. B. STIMPSON.

FASTENING FOR LEGGINS AND OVERGAITERS.

No. 270,147.

Patented Jan. 2, 1883.

UNITED STATES PATENT OFFICE.

EDWIN B. STIMPSON, OF BROOKLYN, NEW YORK.

FASTENING FOR LEGGINS AND OVERGAITERS.

SPECIFICATION forming part of Letters Patent No. 270,147, dated January 2, 1883.

Application filed July 5, 1882. (Model.)

To all whom it may concern:

Be it known that I, EDWIN B. STIMPSON, of Brooklyn, in the county of Kings and State of New York, have invented a new and useful Improvement in Fastenings for Leggins, Overgaiters, &c., of which the following is a specification.

My invention relates to that class of fastenings which comprise two thin flexible strips 10 of steel or other metal secured in pockets in the overlapping edges of a leggin or overgaiter, and which are provided with devices that may be interlocked to secure the leggin or overgaiter in place. Such fastenings 15 are fastened and unfastened by bowing or springing outward one strip to draw its ends together or shorten it; and my present invention consists in the combination, with the leggin or overgaiter provided with pockets and 20 strips contained entirely within the pockets, of novel devices secured to the strips, as hereinafter described, and which are adapted to be engaged with and disengaged from each other.

25 In the accompanying drawings, Figure 1 represents a face view of the two parts of the fastening. Fig. 2 represents an edge view of the fastening, showing in dotted lines the position which the strip having the studs is made 30 to assume in operating the fastening. Fig. 3 represents a side view of a leggin having the fastening applied, the edges of the leggin being slightly separated; and Figs. 4, 5, and 6 represent slotted plates of modified form which 35 may be employed.

Similar letters of reference designate corresponding parts in all the figures.

A B designate two flat and thin strips of metal—such, for instance, as spring-steel—40 which are of about equal length.

To the ends of the strip A are attached plates C, each provided with a U-shaped slot, a, and with overhanging lips or flanges b, which are raised from the face of the strip, so 45 as to leave a space between the said lips or flanges and the strip about equal in width to the thickness of the plates. The strip A is adapted to be inserted in a pocket, D', in the edge of the leggin D, and the two plates C are 50 to be placed outside the pocket, as shown

clearly in Fig. 3. The strip may then be secured to the leggin and the plates C to the strip by inserting the rivets c directly through the plates, the material of the leggin, and the strip.

In lieu of rivets c, the plates C might be provided with prongs d, (shown in Fig. 4,) which are adapted to be bent up at an angle to the plate and inserted through holes or notches in the strip, and also through the material of 60 the leggin, and then folded over, as shown in Fig. 5.

The strip B is adapted to be inserted in a pocket, D', in the opposite edge of the leggin D; and e designates studs which are inserted 65 through the material of the leggin and the strip B and riveted. The studs e are button-headed, or are provided with flanges. The necks of the studs e are adapted to enter the slots a freely, the head of the stud passing 70 under the lips or flanges b on the slotted plate C, and the stud cannot be withdrawn from the slotted plate until it is first moved longitudinally beyond the lips or flanges.

The manner of operating this fastening is 75 clearly shown in Fig. 2. One of the studs e—the lower one, for instance—is slipped into engagement with the lower slotted plate, C, as shown in Fig. 2, and the strip B is then bowed outward, so as to reduce the length sufficiently 80 to allow the stud at the upper end of the strip B to enter the slotted plate at the upper end of the strip A. The strip B is then released, and the upper stud moves up under the lips or flanges b, and the leggin is fastened. To 85 unfasten the leggin the strip B is bowed or sprung out sufficiently to carry the upper stud e beyond the lips or flanges of the upper plate C, and the lower stud may then be readily withdrawn from the lower plate C.

Instead of employing a plate C of the form before described, I may use a plate of the form shown in Fig. 6. In this plate the slot a extends from a hole, f, large enough to permit the passage of the head of the stud, which 95 then moves longitudinally under the lips or flanges b.

What I claim as my invention, and desire to secure by Letters Patent, is—

The combination, with a leggin or over-

gaiter provided with the pockets D' D^2 , of the strips A B , contained entirely within said pockets, the slotted plates C , provided with the lips or flanges b on the outside of the pocket D' , 5 rivets or fastening devices for securing said plates to the strip A , and the studs e , secured in the strip B , and provided outside the pock-

et D^2 with heads or flanges, substantially as and for the purpose specified.

E. B. STIMPSON.
